CLAIM

The ornamental design for a wrist ankle weight, as shown and described.

DESCRIPTION

FIG. 1 is a front, right side perspective view of a wrist ankle weight, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a rear, right side perspective view of the wrist ankle weight; and,

FIG. 9 is an enlarged view of a portion labeled, 'FIG. 9' in FIG. 1.

The dot dash-lines shown on the wrist ankle weight depict stitching that form no part of the claimed design. The dash dot dash lines in FIGS. 1 and 9 are for the purpose of depicting the cut line of the enlarged view and form no part of the claim.
